CENTRIFUGAL IMPACT MILLER
FOR CEREALS

Franklin S. Smith, Hamden, Conn.

Application August 13, 1948, Serial No. 43,983

6 Claims. (Cl. 241—275)

1

This invention relates to disintegration, and more particularly to the "break" operations in milling of cereals such as wheat.

An object of this invention is to provide for the disintegration of flowable bulk products in an improved manner. A further object is to provide a highly efficient system for impacting products such as cereals and cereal products. A further object is to provide an improved apparatus for performing the break operations in the milling of cereals such as wheat. A further object is to provide apparatus for carrying out the above in an efficient and dependable manner, with the apparatus being simple and sturdy in construction, relatively inexpensive to build and operate and thoroughly efficient and dependable in use. These and other objects will be in part obvious and in part pointed out below.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the drawings in which is shown one illustrative embodiment of the invention:

Figure 1 is a vertical section of one embodiment of the invention with certain parts being shown in full lines;

Figure 2 is an enlarged perspective view of a stationary multitarget member which is one element of the embodiment of Figure 1;

Figure 3 is a sectional view on the line 3—3 of Figure 2;

Figure 4 is a bottom plan view of the multitarget member of Figures 2 and 3;

Figure 5 is a top plan view of the apparatus of Figure 1 with parts broken away to show the internal structure; and,

Figure 6 is an enlarged fragmentary sectional view on the line 6—6 of Figure 1.

In my co-pending application Serial No. 553,017, filed September 7, 1944, which issued as Patent No. 2,501,622, on March 21, 1950, there is disclosed a method and apparatus for treating products and specifically for carrying on the disintegration of a product such as the milling of wheat. The present invention is related to and in some respects is an improvement upon the invention of that co-pending application.

In that co-pending application there is disclosed an improved impactor construction and the impactors are illustratively shown as members mounted on a rotor. In the illustrative embodiment

2

ment of the present invention, members of this same general construction are used, but they are rigidly mounted on the stationary frame or shell construction around the rotor so as to form multi-targets. The product is then impelled through the rotor and projected against the stationary targets to obtain the impacting action. Thus in some respects the impacting action differs from that of the illustrative embodiment of the invention of my co-pending application.

Referring particularly to Figure 1 of the drawings there is disclosed a housing 2 having a main casting, forming a top shell 4, and a hopper bottom 6 bolted to shell 4. Housing 2 is supported by three legs 8 (see Figure 5) each of which (see Figure 1) is received at its upper end in a socket 9 formed in a bracket 10 integral with shell 4. Legs 8 are held in sockets 9 by a push fit, and the lower end of each leg is provided with a floor flange or foot 11. Mounted on top shell 4 is an electric motor 14 which has three legs 12 clamped to shell 4 by studs. Motor 14 has a downwardly projecting shaft which extends through an elongated bearing structure 16, which includes a lower heavy duty roller type bearing 17 (indicated in broken lines), and terminates in a tapered extension 18.

Shell 4 has a central product inlet opening 20 which is surrounded by a downwardly extending collar 22, and which receives a stream of the product from a chute 24 which terminates directly over the opening. Chute 24 is supported by an annular flange 26 resting upon and held by screws to the top of shell 4, and the chute has an opening 28 in its top wall through which the bearing structure 16 projects. As shown best in Figure 5, chute 24 terminates at collar 22 on one side of its longitudinal center line in a lip 29, and on the other side of this center line the chute extends into collar 22 (see also Figure 1) and terminates in a lip 30. Lip 30 extends radially of opening 20 and is cut away to fit the outer wall of the bearing structure 16.

Fixed to the tapered extension 18 of the motor shaft, by a nut 32, a washer 34 and by a conventional key and key ways (not shown), is a rotor 36 which is concentrically positioned directly beneath the product inlet opening 20. Rotor 36 is formed by a lower dish shaped base member 38 and a top member 40 rigidly connected together. Member 38 has a central hub portion 39 which is surrounded by an upwardly and outwardly extending wall which terminates in an annular flange 41 which presents an upper flat annular surface 42. Member 40 is generally annular but has adjacent its outer edge a number of equally

spaced flat radial vanes 44, which are illustratively seventy-two in number and which project downwardly and with bottom surfaces which abut surface 42 of member 38. These vanes are of the cross-sectional configuration shown best in Figure 6 with each having a leading surface 46, a trailing surface 48 and end surfaces 50 and 51. As indicated in broken lines in Figure 6, alternate vanes 44 are attached to member 38 by cap screws 52 which secure members 38 and 40 together so as to form the rigid rotor structure. Equally spaced around the rotor are four "Woodruff" keys 54 which ensure that the two members are in accurate alignment and transmit the torsional load. The rotor 36 is shaped as shown with variable thickness for substantially uniform stress distribution; and so that its center of gravity coincides with the center of the lower bearing 17 of the motor 14; as indicated above bearing 17 is preferably of the heavy duty roller type and is located near the lower end of the elongated bearing structure 16. Rotor 36 and the rotor of motor 14 are dynamically balanced before installation; but due to probable load unbalance it is desirable to position rotor 36 as described to prevent bending of the motor shaft and excessive vibration.

Surrounding the outer periphery of rotor 36 is a circular row of multitargets or multitarget members 56 which are illustratively sixty in number and which are rigidly mounted in cylindrical holes or recesses 57 in the top wall of shell 4. These multitarget members are of the construction shown best in Figures 2 to 4 and are formed by a body portion 58 and three elongated flat parallel targets 60, 62 and 64 with apertures 61 and 63 therebetween. The central target 62 is tapered from one edge to the other so that apertures 61 and 63 are tapered transversely as shown. The targets have identical shanks at their upper ends which are received in slots in the body member; three slots are separated by walls 66, and two bolts 68 having nuts 69 extend through the target shanks and walls 66 so as to securely clamp the targets and body member together. The heads and nuts of bolts 68 are positioned in recesses so that the body member presents an unobstructed outer cylindrical surface 70, except that at the top of this surface there is a pin 72 which is press fitted into a hole in the body member and has its end projecting beyond the surface. As indicated above, these multitarget members are snugly received in recesses 57 in shell 4, and at the top of each recess there is a radial positioning slot which snugly receives the projecting end of the pin 72 of the impactor positioned in that recess.

Thus, the multitarget members form an array of discrete targets illustratively one hundred and eighty in number and collectively designated by the numeral 77 and these targets are spaced from and concentric with rotor 36 and depend from an annulus on the upper wall of shell 4. As shown best in Figure 1, the vertical extent or length of these targets exceeds the vertical extent of the annular outlet from rotor 36, and the targets form with a frusto-conical surface 78 of shell 4 a diffusion zone 79, the purpose of which will be explained below. When desirable the targets may be equally spaced around the annulus with intervening uniform apertures therebetween.

During operation, the rotor turns counterclockwise, and pins 72 are positioned as shown with respect to the targets 60, 62 and 64, and the positioning slots in recesses 57 are symmetrically related to the axis of the rotor, which is the main axis of the machine, so that each of the multi-

target members has its targets positioned the same with respect to the rotor, as shown in Figures 5 and 6. Specifically, each multitarget member (see Figure 6) is positioned with its apertures 61 and 63 approximately on a tangent from the periphery of rotor 36 in its rotational direction; that is, counterclockwise as indicated by the arrow in Figure 6. The multitarget members are mounted sufficiently close to each other so that no tangent from the rotor periphery passes between adjacent members, and each overlaps its adjacent multitarget members transversely of the tangential flow of the product by approximately one-half the width of these members.

Each target presents a target face or impacting surface which is substantially transversely of the direction of tangential flow of the product discharged from the rotor. The three target faces provided by each multitarget member are 15 equally spaced by the apertures 61 and 63, and each set of these target faces overlaps the two adjacent sets. Thus, as the product is projected from the rotor it tends to move toward the various target faces substantially normal thereof and impacts against these faces. Some of the air accompanying the product flows through apertures 61 and 63, and some is deflected outwardly and downwardly. As indicated above, the apertures are tapered so that their widths increase 20 progressively away from the impact faces, and therefore, any product particles which enter the apertures are quickly released.

Each multitarget member 56 has at its top a rim 73 which rests on the top surface of shell 4 and aids in positioning the multitarget member in its recess, and each multitarget member has an upward projection 74 which has a transverse hole 76 near its top. During the positioning of the multitarget member a tool is positioned in the hole 76 for turning the multitarget member so that the end of pin 72 will mate with its recess in the shell as the multitarget member is moved downwardly in place. Hole 76 is also used when the multitarget member is to be withdrawn, for inspection, repair or replacement, without further dismantling of the machine.

Referring again to Figure 1 of the drawings, a stream of the product passes by gravity down chute 24 and substantially one-half of the product is directed by lip 30 in the direction of rotor rotation to the central portion of rotor 36, while the remainder of the product falls over lip 29 directly upon the central portion of the rotor. The lower edge of collar 22 tends to even the product flow to the contiguous dish-shaped portion of the rotor. The rotary movement of the rotor causes the product to spread out and flow in an even annular stream at an increasing rate upwardly along the dish-shaped upper surface of the rotor. As the stream reaches the inner edge of surface 42 segments of the stream are picked up by vanes 44 on their leading surfaces 46 so that the stream is divided into a large number of small streams. Each of these streams spreads out upwardly along its surface 46, while the speed of flow is increased and this causes a further thinning out of the stream.

The product and accompanying air are discharged from the outlet of rotor 36 through the trajectory zone 80 to the array of discrete targets 77. The trajectories of the product particles, such as the grains of wheat, are somewhat turbulent but flow in a generally tangential direction and at a velocity to cause disintegration or shattering upon impact with said array of tar-

gets. The product particles which do not directly impinge upon one set of target faces are guided by the side surface 82 of the adjacent target member 60 to the target faces of the next adjacent multitarget in the trajectory direction. By reason of air flow through apertures 61 and 63 and the passageways between the multitargets into the relatively large diffusion zone 79 beyond the target array, eddy air currents within the trajectory zone are greatly diminished. Therefore, cushioning and deflection of the product particles near and at the target faces are substantially eliminated with resultant shattering of all the product particles.

Some of the shattered product is carried into the diffusion zone 79 and from there by gravity and air currents through the discharge opening at the bottom of the hopper, and the balance of the shattered product is carried by gravity and air currents directly from the target faces downwardly through the hopper discharge opening.

The illustrative embodiment of the invention is particularly adapted for the "break" system in the milling of wheat. When so used in one particular instance, the rotor was 28 inches in diameter and was rotated at 1740 R. P. M. The target array was spaced from the periphery of the vanes substantially $\frac{3}{4}$ of an inch and the other dimensions are shown on the drawing substantially to scale. This machine has general application for disintegrating various products and it should be understood that the number of vanes on the rotor and the number of stationary targets, as well as other characteristics of the machine, may be varied to suit particular uses and conditions of operation. Furthermore, the vanes may be curved, or inclined forwardly or rearwardly. The dimensions of the target faces and intervening apertures should be chosen to effectively treat a given product. In general, the height of the targets should exceed the height of rotor outlet, the width of the intervening apertures should be less than the average minor dimension of the product, and the face of the target may be wider or narrower than the average major dimension of the product, all depending upon the sort or break or shattering desired.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. In apparatus of the character described, a casing construction comprising a top shell portion having a central product-inlet opening at the top and a hopper portion at the bottom through which the product is discharged, a rotor mounted within said casing construction and adapted to receive a product flowing into said inlet opening, said rotor having a plurality of radial vanes which are adapted to direct the product so that it discharges substantially tangentially from the periphery of the rotor, and a plurality of stationary multitarget members mounted in the path of the product flowing from the edge of said rotor, each multitarget member comprising a plurality of spaced targets having flat leading edges, said flat leading edges being normal to the flow of the product leaving the periphery of said rotor, said target members being

positioned in an annular row around the periphery of said rotor and being so positioned with respect to each other that any particle of grain passing around a target member or through the slots between the targets thereof engages the leading edge of one of the targets of the next multitarget member.

2. In apparatus of the character described, in combination, a casing including a top shell portion having a product-inlet opening at the top and a hopper at the bottom through which the treated product is discharged, a rotor mounted within said casing beneath said product-inlet opening, said rotor having a plurality of radial vanes which are adapted to direct the product to the periphery of the rotor so that it discharges substantially tangentially from the periphery of the rotor, and a plurality of multitarget members spaced from and surrounding the periphery of said rotor, each multitarget member having a substantially flat target face positioned substantially normal to the direction of flow of the product leaving the edge of said rotor, said multitarget members having their faces positioned in overlapping relationship with respect to each other.

3. In apparatus of the character described, a casing construction comprising a top shell portion having a central product-inlet opening at the top and a hopper portion at the bottom through which the product is discharged, a rotor mounted within said casing construction and adapted to receive a product flowing into said inlet opening, said rotor having a plurality of radial vanes which are adapted to direct the product so that it discharges substantially tangentially from the periphery of the rotor, and a plurality of stationary multitarget members mounted in the path of the product flowing from said rotor, each of said multitarget members comprising a plurality of elongated substantially flat targets positioned in side-by-side parallel relationship with each target having a substantially flat edge surface forming a target face positioned substantially normal to the direction of flow of the product, at least one of said target members being tapered from its thicker edge at the target face to its thinner opposite edge, the outer targets having their side walls in planes aligned with the direction of flow of the product.

4. In apparatus of the character described, a casing construction comprising a top shell portion having a central product-inlet opening at the top and a hopper portion at the bottom through which the product is discharged, a rotor mounted within said casing construction and adapted to receive a product flowing into said inlet opening, said rotor having a plurality of radial vanes which are adapted to direct the product so that it discharges substantially tangentially from the periphery of the rotor, a plurality of stationary multitarget members mounted in the path of the product flowing from said rotor and each comprising a plurality of individual targets rigidly mounted in spaced relationship, each multitarget member having a cylindrical body which is snugly received in a hole in the shell portion, and means forming a protrusion on the body of each multitarget member which is adapted to fit within a slot contiguous with each hole whereby the relative angular position of each multitarget member is fixed with respect to the rotor.

5. In apparatus of the character described, in combination, a rotor comprising a dish-shaped base member having a central hub, an outwardly

and upwardly extending peripheral flange, a substantially horizontally positioned flange extending outwardly from said last-mentioned flange, a top portion of generally annular shape, and a plurality of vanes positioned between said top portion and said horizontally positioned flange portion, a drive shaft secured to and extending upwardly from said hub, a bearing for said drive shaft located between said hub and said top portion, a product-inlet extending downwardly into the dish-shaped base member of said rotor, the lower end of said product-inlet being positioned below the plane in which the horizontally positioned flange portion of said rotor is positioned, and a plurality of targets positioned around the periphery of said rotor, said targets being positioned in the path of the product leaving the edge of said rotor.

6. In apparatus for milling cereals such as wheat, in combination, a rotor comprising a dish-shaped base member having a central hub, an outwardly and upwardly extending peripheral flange, a substantially horizontally positioned flange extending outwardly from said last-mentioned flange, a top portion of generally annular shape, and a plurality of vanes positioned between said top portion and said horizontally positioned flange portion, a drive shaft secured to and extending upwardly from said hub, means forming a bearing for said drive shaft located between said hub and said top portion substan-

tially at the center of gravity of said rotor, a product inlet extending downwardly into said rotor, and a plurality of targets positioned around the periphery of said rotor, said targets being positioned in the path of the product leaving the edge of said rotor.
